UNITED STATES PATENT OFFICE.

JOHN J. BYRNE AND CLARENCE D. HEUBECK, OF BALTIMORE, MARYLAND.

STILT.

Application filed October 1, 1924. Serial No. 741,027.

To all whom it may concern:

Be it known that we, JOHN J. BYRNE and CLARENCE D. HEUBECK, citizens of the United States, residing at Woodbury, Baltimore, in the State of Maryland, have invented certain new and useful Improvements in Stilts; and we do hereby declare the following to be a full, clear, and exact description of the same, reference being had 10 to the accompanying drawings, forming part of this specification.

This invention relates to improvements in stilts and has for its primary object to provide a stilt which can be lengthened 15 while a person is walking on them so as to give the effect that the walker is gradually increasing in height. In this respect, the stilt differs from most of the prior stilts wherein the foot rest or support can only 20 be adjusted vertically to a position in which it must remain while the stilt is in use.

A further object is to arrange the mechanism for elongating the stilt whereby said mechanism can be actuated simply by turning 25 the stilt handle, this usually being done to one stilt while the other is supporting the walker's weight.

A further object is to provide an automatically operated mechanism which will 30 render the lengthening mechanism inoperative and which will permit the walker to lower himself without getting off the stilt.

In the accompanying drawings,—

Figure 1 is an elevational view of a stilt 35 embodying the present invention.

Fig. 2 is a longitudinal sectional view of the stilt.

Fig. 3 is a sectional view on the line 3—3 of Fig. 2.

In accordance with the present invention, 40 the stilt is composed essentially of two sections, a tread section 10 and a handle section 11, the two sections being connected together by a nut 12 mounted in one section, 45 preferably the tread section, and a helically threaded screw 13, secured in the other or handle section by a cross pin 15, said screw cooperating with a key 28 in said nut in such fashion that by turning handle section 50 11 it will recede in the tread section, which is hollow, or by rotating said handle section in the opposite direction the screw will be withdrawn from the hollow tread section and the stilt consequently lengthened.

It is preferred that this elongation of the 55 stilt be accomplished gradually and to sup-

port the walker's weight, there is loosely mounted on the screw 13 a ratchet member 14 with which a pivoted pawl 16 cooperates. Said pawl is pivoted in a slot 17 in the screw 60 13 (which is made hollow for a purpose presently to be set forth) and revolves with the screw and handle whereby each time the handle is rotated to elevate the walker the pawl 16 will slip over one or more teeth. 65 The ratchet, however, is held against rotation so that the handle cannot be rotated in the opposite direction and the walker can, therefore, lengthen the stilts, step by step, each time he lifts the stilt off the ground. 70

The means for holding the ratchet against rotation preferably consists of a tubular metallic member 18, attached to the ratchet and formed with one or more longitudinally extending grooves 19 with which radially 75 projecting pins 20 in the nut 12 engage. The foot rest 24 is carried by this tubular member 18. To hold the ratchet in proper position longitudinally of screw 13 where it will properly cooperate with pawl 16 a 80 stop member 21 is secured on the screw by a cross pin 22 and to hold the pawl yieldingly in engagement with said ratchet there is provided a spring 23.

After the person on the stilts has withdrawn the screw from the nut and tread portion a predetermined distance it is preferred that the holding pawl be rendered inoperative so as to prevent total withdrawal 85 of the screw as well as to allow the person on the stilt to gradually let the screw recede in the tread portion to give the effect of the walker growing shorter. He can let himself down gradually or suddenly, if he wishes, as a cushioning element or shock 90 absorber 25 is interposed between stop 21 and nut 12.

In the preferred arrangement for automatically releasing the pawl 16, said pawl is pivoted intermediate its ends with one end 100 projecting into the hollow screw 13. Attached to this end of the pawl is a wire 26 which extends down to the end of the screw where it is attached to a disc 27 whose edge projects beyond the periphery of the screw whereby when said screw has been withdrawn far enough to bring said disc into engagement with nut 12 a further turning of the handle and screw will result in said disc and wire pulling 110 down on the inner end of the pawl and disengaging the pawl from the ratchet.

Preferably the point at which the pressure of spring 23 is exerted on the pawl and the pivoted center of the pawl are so positioned relatively to each other, that the pull of the 5 wire 26 on the inner end of the pawl will move the point of spring pressure past the pivoted center so that the pawl will remain inoperative until the user places his finger against the outer end of the pawl 10 and restores it to operative position.

What we claim is:—

1. In a stilt, the combination of a tread section, a handle section, one of said sections being rotatable with respect to the other, a foot rest, and means operable by rotation of one of said sections for elongating the stilt. 15

2. In a stilt, the combination of a tread section, a handle section rotatable with respect to the tread section, means operable by rotation of the handle section for moving one of said sections longitudinally of the other to elongate the stilt, and a foot rest mounted on one of said sections. 20

3. In a stilt, the combination with a tread section, a handle section rotatably supported on the tread section, a foot rest carried by said handle section, and means operable by rotation of the handle section for moving 30 said handle section longitudinally of the tread section.

4. In a stilt, the combination of a tread section, a handle section rotatably supported on the tread section, a foot rest on the 35 handle section, means operable by rotation of the handle section in one direction to move said section longitudinally of the tread section, and means for releasably locking the handle section against rotation in the opposite direction. 40

5. In a stilt, the combination of a tread section, a handle section rotatably supported on the tread section, a foot rest on the handle section, means operable by rotation 45 of the handle section in one direction to move said section longitudinally of the tread section, means for releasably locking the handle section against rotation in the opposite direction, and means for releasing the locking means when the stilt has been elongated to a predetermined length. 50

6. In a stilt, the combination of a tread section, a handle section rotatably supported on the tread section, a foot rest, a helically 55 threaded screw mounted in the handle section, a nut carried by the tread section keyed on said screw, and means for holding said nut against rotation whereby rotation of the handle will cause said handle and the 60 screw carried thereby to move longitudinally of the tread section.

7. In a stilt, the combination of a tread section, a nut mounted in said section, a handle section, a foot rest, a helically 65 threaded screw mounted in the handle sec-

tion and cooperating with said nut, said handle and screw being rotatable with respect to the tread section and nut, a locking member loose on the screw and provided with a circular series of indentations in one 70 face, means for preventing rotation of said locking member, and a pawl cooperating with the indentations in said locking member for locking said handle and screw against rotation in one direction. 75

8. In a stilt, the combination with a handle section and a tread section rotatable with respect to each other, a foot rest, a nut secured in one of said sections, a helically threaded screw secured in the other section 80 and cooperating with said nut, and means for releasably locking said sections against rotation in one direction, said locking means comprising a ratchet and a pawl cooperating with said ratchet. 85

9. In a stilt, the combination with a handle section and a tread section rotatable with respect to each other, a foot rest, a nut secured in one of said sections, a helically threaded screw secured in the other section 90 and cooperating with said nut, means for releasably locking said sections against rotation in one direction, said locking means comprising a ratchet and a pawl cooperating with said ratchet, and means for automatically releasing said pawl when said handle and tread sections have been rotated with respect to each other a predetermined 95 number of times to permit the direction of rotation to be reversed. 100

10. In a stilt, the combination of a tread section, a handle section rotatably supported by the tread section, a nut mounted in the tread section, a helically threaded screw secured in the handle section and cooperating with said nut, a ratchet member loose on said screw intermediate the handle and tread sections, a pawl carried by the handle cooperating with the ratchet to hold the handle against rotation in one direction, a tubular 105 member attached to the ratchet and enclosing a portion of said nut, there being cooperating elements on said tube and nut for preventing rotation of the tube and ratchet member. 110

11. In a stilt, the combination of a hollow tread section, a handle section, a nut mounted in the tread section, a helically threaded screw mounted in the handle section cooperating with said nut and telescoping within the hollow tread section, whereby rotation of the handle section will withdraw the screw from the tread section and elongate the stilt. 120

12. In a stilt, the combination of a hollow tread section, a handle section, a nut mounted in the tread section, a helically threaded screw mounted in the handle section cooperating with said nut and telescoping within the hollow tread section, whereby 125 130

rotation of the handle section will withdraw the screw from the tread section and elongate the stilt, a ratchet loose on the screw, a pawl carried by the handle and cooperating with the ratchet to prevent rotation of the handle in the opposite direction, a tubular member carried by the handle section telescoping over the tread section and nut, means on said nut and tubular member for holding the ratchet against rotation, and means for automatically disengaging the pawl from said ratchet when the stilt has attained a predetermined length to allow the stilt to be restored to its original length.

10 13. In a stilt, the combination of a tread section, a handle section, a foot rest, means operable through the handle section for

moving said sections longitudinally apart to elongate the stilt and elevate the foot rest, said sections being returnable to their original contracted condition by weight applied to the foot rest, and means releasably locking the sections in any position during elongation of the stilt.

14. In a stilt, the combination of a handle section, a tread section, a foot rest, means for elongating the stilt and elevating the foot rest by rotation of one of said sections in one direction and for contracting the stilt and lowering the foot rest by rotation in the opposite direction, and means for releasably locking said section against reverse rotation.

JOHN J. BYRNE.
CLARENCE D. HEUBECK.
